UNITED STATES PATENT OFFICE.

EDWARD YOUNG, OF PONY LAKE, NEBRASKA.

MECHANICAL STOKER FOR LOCOMOTIVES.

1,148,735.

Specification of Letters Patent. Patented Aug. 3, 1915.

Application filed October 25, 1913. Serial No. 797,226.

To all whom it may concern:

Be it known that I, EDWARD YOUNG, citizen of the United States, residing at Pony Lake, in the county of Rock and State of Nebraska, have invented certain new and useful Improvements in Mechanical Stokers for Locomotives, of which the following is a specification.

My invention relates to appliances for stoking furnaces, and particularly to mechanism for stoking locomotive furnaces.

The primary object of my invention is the provision of a very simple mechanical stoker designed to discharge coal into the fire box of a locomotive without the necessity of opening the door leading thereto.

A further object of the invention is to provide means whereby the direction in which the coal is discharged may be controlled.

A further object of the invention is to provide means whereby the coal discharged from the stoker may be directed either to the right or left of the fire box, and to provide independent means for discharging the coal either directly downward or toward the front of the fire box.

A still further object of the invention is to provide means whereby the coal may be discharged from the stoker at varying velocities so as to throw the coal either to the forward end of the furnace or the rear end thereof, and a still further object is to provide mechanism entirely within the control of the fireman whereby the speed of the stoker and the direction of its movement may be controlled.

Other objects will appear in the course of the following description.

My invention is illustrated in the accompanying drawings, wherein:

Figure 1 is a vertical longitudinal section of the rear portion of a locomotive, my improved stoker being shown in section. Fig. 2 is a horizontal section through the stoking mechanism. Fig. 3 is a transverse section on the line 3—3 of Fig. 2. Fig. 4 is a side elevation of the stoker illustrated in Figs. 1, 2 and 3. Fig. 5 is a plan view of the means for operating the stoker with parts in section. Fig. 6 is a detail view of the shaft 6 with one of the gears thereon in section.

Corresponding and like parts are referred to in the following description and indicated

in all the views of the accompanying drawings by the same reference characters.

Referring to Fig. 1, it will be seen that the locomotive to which the stoker is applied is of the usual type and includes the cab A, the furnace B having the usual fire box and grate, and the inner and outer crown sheets C and D. The deck of the cab is designated E. All these parts are of any usual or ordinary construction and I do not wish to be limited to any special construction of locomotive.

Mounted upon the deck E in front of the boiler is a casing 2 which may be made of any suitable refractory material and is illustrated as made of metal. This casing is in the form of a relatively wide and relatively shallow box, the rear end of the box being curved in the arc of a circle, the forward end of the box being open. The box is formed of the upper and lower members 3 and 4 and the vertical wall 5 flaring outward at its forward ends.

Passing up into the box and mounted in suitable bearings therein is a shaft 6 carrying a plurality of radiating blades 7 illustrated as four in number, though I do not wish to limit myself to this number. These blades as illustrated are arranged in quartering relation to each other and the rear portion of the wall 5 is curved concentrically to the shaft 6. The blades 7 have a height approximately equal to the depth of the casing 2.

As previously stated, the forward end of the casing is open and this forward end of the casing projects through the crown sheets C and D, and opens into the furnace B above the grate thereof. Hingedly mounted upon the forward open end of the casing 2 is the gate or door 8 having a width equal to the width of the open end of the casing and having an arm 9 extending above the hinged axis of the door from which rearwardly extends a connecting rod 10 into the cab where it is connected to a lever 11 pivotally supported in any suitable manner. The link or connecting rod 10 may pass through a thimble 12 disposed between the sheets C and D. Any preferred means may be employed for holding the lever set in any adjusted position. By actuating the lever in one direction, the door 8 may be turned upon its axis to raise it to any required degree. When

the door 8 is raised to a horizontal position, the coal discharged from the casing will be thrown forward so as to be discharged upon the forward portion of the fire box. When 5 the door is in the position shown in Fig. 1 and is inclined downward and forward, the coal will be discharged downward and forward upon the grate. It will thus be seen that this door 8 provides means for discharging the coal either upon the front or rear portion of the fire box.

The casing 2 has a width smaller than the width of the furnace and means must therefore be provided for discharging the coal 10 laterally to one side or the other from the discharge end of the casing. For this purpose I provide the deflectors 13, each of them hingedly mounted at the forward end of the wall 5. These deflectors when closed 15 extend as illustrated in full lines in Fig. 2 to the door 8 and form continuations of the ends of the wall 5. These deflectors may however, be rocked upon their bearings to the position shown in dotted lines in Fig. 20 2. To this end the upper plate 3 of the casing 2 is formed with arcuate slots 14 and the forward edge of each door is formed with a pin 15 which passes up through the corresponding slot and is connected to a 25 transversely extending link 16. This link is operatively connected to a lever 17 or other suitable actuating means disposed within the cab. By shifting this lever to the right or to the left, both deflectors will be swung 30 simultaneously either to the right or to the left from a position where they form continuations of the wall 5. When swung to the position shown by dotted lines in Fig. 2, it will be seen that the coal will be discharged to the left of the fire box, while 35 when swung in the reverse direction the coal will be discharged to the right. Of course, the forward end of the vertical wall of the casing must be outwardly flared to 40 accommodate the oscillations of the deflectors, as illustrated in Fig. 2, these outwardly flared portions being designated 18. The top of the casing at its rear end is 45 formed with the opening 19 and hopper 20 whereby coal may be delivered by the fireman into the casing 2 and engaged by the 50 blade 7.

While I do not wish to limit myself to any special means for operating the shaft 55 6, this shaft is preferably operated by independent driving mechanism under the control of the fireman. This driving mechanism should be independent of the driving mechanism of the engine so that the 60 stoker may operate when the engine is standing still and the speed of the driving mechanism and the direction of rotation of the blades 7 should be under the control of the engineer so that the coal may be cast 65 either into the forward portion of the fire-

box or into the rear portion thereof and so that the stoker may cast either to the left or to the right. To this end I have illustrated the shaft 6 as being driven by a pair of steam cylinders 21, each having a piston 22, the piston being formed with teeth 23.

24 designates the valve casing controlling the admission of steam to the cylinders 21 and within this casing operates a valve controlled by a valve rod 25 which extends outward and is connected to a pivoted arm 26 which is oscillated by engagement with the spaced pins 27 on the rod 22, in a manner which will be well understood by those cognizant of the art.

It will be obvious that some form of ratchet mechanism must be provided between the piston rods 22 and the shaft 6 so that a reciprocation of the piston rods will cause the rotation of the shaft 6 in one direction only.

While I do not wish to limit myself to any special mechanism for this purpose, I have illustrated upper and lower gear wheels 28 as mounted loosely upon the shaft 6 and these wheels may be held against dropping by any convenient means, such as collars secured upon the shaft. Each of these gear wheels, as illustrated clearly in Figs. 5 and 6 is formed upon one side with a semi-circular recess 29 eccentric to the opening through which the shaft 6 passes. This recess is crescent shaped. A longitudinally shiftable partition 30 is shiftably mounted on the shaft 6 in connection with each of the toothed wheels 28 and is shiftable into or out of the space 29. Located in the space 29 is a ball 31, this ball being smaller in diameter than the widest portion of the space 29. When the ball 31 is on one side of the partition 30 it will clamp the gear wheel 28 to the shaft 6 for rotation in one direction but will free the wheel 28 from engagement with the shaft 6 upon a rotation of the gear wheel in an opposite direction. When, however, the ball 31 is disposed on the opposite side of the partition 30 it will exert a reverse binding action. It will therefore be seen from Fig. 5, for instance, that upon an outward movement of the piston in the direction of the arrow, the shaft 6 and gear wheel 28 will be freed from engagement with each other but that upon an inward movement of the piston in the direction opposite to the arrow, the gear wheel 28 will be locked to the shaft 6 and the shaft will rotate in the direction of the curved arrow. The pistons of the two cylinders operate alternately to each other and therefore a practically continuous rotation 125 will be given to the shaft at a speed depending upon the amount of steam admitted to the cylinders 21. For the purpose of reversing the direction of movement of the shaft 6 I provide each partition with a 130

shipper sleeve 32, the shipper sleeve being connected by means of a yoke 33, as illustrated in Figs. 1 and 4, this yoke being connected to a lever 34, in turn connected to a handle 35 extending up into the cab of the engine. When it is desired to rotate the shaft in one direction, the handle 35 is operated to shift the partitions 30 out of the spaces 29. Immediately that this occurs the balls will roll into the end of the spaces 29 on the other side of the partition. The partitions are then again closed or inserted within the space 29, whereupon the balls will reversely engage the gear wheels of the shaft and the shaft will be rotated in a reverse direction. The speed of rotation of the shaft may be controlled by a throttle valve 36 operated within the cab and operatively controlling the supply of steam to the cylinders 21.

The operation of my invention will be obvious from what has gone before. Continuous rotary motion is preferably given to the blades 7, though it is, of course, obvious that the blades may be rotated only when desired. Coal is thrown into the hopper 20 and if the door 8 be open, this coal will be ejected through the discharge end of the casing onto the fire and the direction in which the coal will be ejected will be controlled by the door 8 and by the deflectors 13. It will be seen that the blades 7 form a closure for the casing and therefore that there can be no back draft at any time if the blades 7 be still. When the blades 7 are rotating, however, it is obvious that they will not cause any back draft. Thus there is no necessity for opening the furnace door in order to stoke the furnace. Inasmuch as the casing 2 is disposed beneath the usual fire door 27, it will be obvious that if the mechanism breaks down, the furnace may be stoked in the usual way. By controlling the speed of rotation of the blades 7 it is possible to cast the coal either into the forward portion of the fire box into the middle thereof or the rear end of the fire box, and this will, of course, be assisted by the door 8. If it is desired to discharge the coal toward the side of the fire box, the deflectors are appropriately inclined and the direction of rotation of the blades changed so that the coal will be discharged on that side.

The advantages of my invention reside in the fact that by this mechanism I can secure a more uniform distribution of the coal than is possible where the coal is shoveled into the furnace, that the operation of stoking is much more rapid, that the fireman is relieved of very heavy manual labor and that inasmuch as the coal is more uniformly spread, the coal is used more economically than is possible where the coal is hand stoked.

While I have illustrated what I believe to

be the best form of my invention, I do not wish to be limited to this as it is obvious that the construction may be varied in many ways without departing from the spirit of the invention.

70

What I claim is:

1. The combination with a locomotive including a cab and a fire box, of a casing mounted in connection with the fire box and having an open end extending into the fire box, said casing having an aperture opening into the cab, a vertically disposed shaft in the casing, radially disposed vanes on the shaft, means for rotating said shaft, a swinging door within the fire box hingedly mounted at its upper end to the open end of the casing, means extending into the cab for operating said swinging door, laterally disposed deflectors within the fire box mounted upon the casing at its open end in rear of said door, said deflectors being connected to each other externally of the casing for simultaneous movement in the same direction, and means disposed within the cab for operating said deflectors.

90

2. A mechanical stoker including a casing open at one end and closed at the opposite end and having a fuel receiving opening in its top adjacent its closed end, means disposed within the casing acting upon the fuel and discharging it through the open end of the casing, a door hingedly secured to the upper wall of the casing at the open end thereof and adapted to cover said end, means on top of the casing for angularly adjusting the door, lateral deflectors forming the sides of the casing at the open end thereof adjacent and in rear of said door and shiftable to a position of angularity with respect to the rear side walls of the casing, and means on top of the casing for shifting said deflectors.

95

3. A mechanical stoker comprising a casing having an open end, horizontally swinging deflectors pivotally mounted adjacent the open end of the casing and forming the sides thereof at said end, the casing being provided in a horizontal wall with arcuate slots arranged concentrically with the pivots of the respective deflectors, pins extending from the respective deflectors through said slots, a link external to said casing connecting said pins, means mounted on the casing acting on said link to move said deflectors simultaneously on their pivots, and means within the casing for discharging fuel past said deflectors and through the open end of the casing.

110

4. The combination of a casing having an arcuate closed rear end, closed sides and an open front end and provided with a feed opening in its top adjacent its arcuate end, a vertical shaft in the casing concentric with the arcuate end thereof, radial vanes carried by said shaft to move past the feed

120

125

130

opening below the same, means below the casing to rotate said shaft, means below the casing to control the speed and direction of rotation of the shaft, a door hinged at its upper edge to the top of the casing at the open front end thereof, means on the top of the casing to adjust said door, deflectors mounted in the casing by vertical pivots adjacent the open front end and at

the sides of the casing, and means on the top of the casing for swinging said deflectors laterally simultaneously.

In testimony whereof I affix my signature in presence of two witnesses.

EDWARD YOUNG. [L.S.]
